UNITED STATES PATENT OFFICE.

JOLLY WILBUR THURSTON, OF RICHMOND, VIRGINIA.

GASOLINE-DISPENSING PUMP.

Application filed July 23, 1926. Serial No. 124,504.

An object of this invention is the provision of a gasoline dispensing apparatus of a construction whereby a determined quantity of gasoline or like fluid is pumped into a trans-
5 parent tank or container, and wherein any predetermined quantity of such gasoline, or all of the gasoline may be withdrawn therefrom in an accurate and positive manner so that the purchaser will obtain the exact
10 amount of the fluid ordered.

A further object is the provision of a gasoline dispensing apparatus or pump in which a transparent tank or container is employed, the same having indicators therein to determine the varying levels of the gasoline in the tank, there being a hand operated pump for forcing gasoline into the tank, an overflow pipe for preventing the inflow of gasoline above a predetermined level, a discharge tube 20 movable through the bottom of the tank and through a discharge chamber in the standard for the tank, the latter being provided with a valve controlled outlet, and the discharge tube having associated therewith an operating rod against whose handle portion swingable stop members, corresponding in number, and spaced equidistantly with respect to the indicators in the tank are singly movable so that the gasoline can be accurately dispensed
25 in desired quantities and a back-flow of unused gasoline into the tank will be prevented.

A further object is the construction of an apparatus for this purpose in which the parts constituting the same may be easily associated
35 to produce a firm up-right structure; in which the gasoline may be dispensed in desired quantities in an easy and accurate manner, and in which the construction is comparatively simple and may be cheaply manufactured.

To the attainment of the above broadly stated objects the improvement further resides in certain other novel features of construction, combination and operative association of parts, a satisfactory exemplification of which is disclosed by the accompanying drawings.

In the drawings:

Figure 1 is a side elevation of the improvement.

Figure 2 is a central transverse sectional view through the same.

Figure 3 is an enlarged central sectional view through the upper portion of the improvement.

Figure 4 is a sectional view on the line 4—4 of Figure 3.

Figure 5 is a sectional view on the line 5—5 of Figure 3.

Figure 6 is a sectional view on the line 60 6—6 of Figure 2.

Figure 7 is a sectional view on the line 7—7 of Figure 2.

Figure 8 is a sectional view on the line 8—8 of Figure 7.

Figure 9 is a detail perspective view of the upper ring member and the brace rods associated therewith.

It is essential that the hollow body or standard on which the transparent gasoline tank 70 or container is supported, be erected in a firm and vertical upright position. Therefore, upon the concrete bed that covers the supply tank I bolt the substantially bell-shaped base 1 of the standard. This base, adjacent to 75 its upper inwardly flanged top 2, is formed with an outer annular bead that provides an upper shoulder 3 and on this shoulder there rests the outer hollow casing or standard 4 of the improvement.

Passing through the flanged top 2 of the base 1, at equidistantly spaced intervals, there are rods 5. The ends of these rods are beveled, and the lower ends of the said rods are engaged by nuts 6—6 which contact with both 85 the upper and lower faces of the flange 2. The opposite ends of the rods pass through openings in a flanged ring 7, and these ends of the rods are engaged by nuts 8—8 which contact with both the faces of the ring 7. 90 The casing or standard 4 has its upper end received in the annular depression provided by the flanged ring 7. Resting on the top of the ring 7, and likewise contacting with the outer periphery thereof and surrounding 95 the upper portion of the casing 4, there is the lower flanged end of an outwardly bulged collar 9. The inwardly extending mouth of the collar 9 is formed with an upstanding flange 10 and surrounding this flange and 100 resting on the top of the collar there is the outer peripheral flange 11 on the metal base or support for the transparent tank or container. The periphery of the base 12 is substantially U-shaped in cross section and is 105 therefore hollow. The inner annular flange thus provided is formed with a shoulder depression 13. The ring 7, between the openings that receive the rods 5 therethrough, is formed with other and smaller openings, and 110

through these openings there are passed threaded rods 14, there being screwed on the said rods nuts 15 that contact with the opposite faces of the ring 7, while the second ends 5 of the rods 14 are screwed in the base 12.

Resting on the shoulder 13 of the metal base 12 there is the lower end of the transparent tank or container 16. The upper end of this container 16 is received in an annular groove 10 formed on the lower face of a disc 17. Screwed through the top of the U-shaped periphery of the base 12 there are rods which are likewise screwed through the disc 17, and these rods have screwed thereon nuts 18 which 15 contact with the outer face of the disc 17 to hold the same in tight engagement with the tubular transparent tank or container 16. The disc 17 provides the top for the tank 16, the center of the said disc being covered by 20 a plate 19 that has a vent opening 20 therethrough.

Arranged to surround the disc 17, and held properly spaced therefrom by the rods 21 that have screwed thereon the nuts 18, there is the 25 hollow flanged cap 22 of the improvement. The cap has inner ribs 23 that rest on the disc 17, and the rods 21 may have their outer ends headed or have screwed thereon nuts 24 that contact with the cap. The cap is 30 centrally formed with a vent opening, and this cap may be also provided with a signal, such as a globe 25, (Figure 1) that may encase an electric lamp bulb, the signal 25 being transparent.

35 The opposite sides of the transparent tank or container 16 may be protected by segmental grates 26, and in the tank, centrally between the confronting ends of these grates, and secured to the top and bottom of the 40 said tank, there are vertical rods 27. Adjustably fixed on each of these rods there is an indicator finger 28. Each finger has a socket body 29 that is slidable on the rod 27, a binding element 30 holding the indicator fingers 45 properly positioned with respect to each.

In the showing of the drawings the tank is 50 designed to contain ten gallons of fluid, and this fluid is pumped into the tank by a hand operated pump 31 connected to an inflow pipe 32, the latter being made up of any desired number of sections and the confronting ends of two of these sections are screwed in a boss in the metal base 12 of the tank 16. The upper end of the pipe 32 is disposed a distance 55 above the uppermost indicators 28 so that one gallon of fluid will fill the space between the top of the pipe and the said indicators. The top of the pipe 34 is surrounded by a shield 33. The overflow pipe has its top level 60 with that of the pump pipe 32. This pipe 34 is also constructed of any desired number of sections, the confronting ends of two of such sections being screwed in a second boss in the tank base 12.

65 Screwed through the bottom of the base

12 and received in the collar 9 there is a coupling 35. The upper end of this coupling is engaged by a screw member or nut that holds a packing 36 in the said coupling. The lower end of the coupling is widened and has 70 screwed therein a tubular member that provides a gasoline discharge chamber 37. The coupling has an angle branch in which is screwed a pipe provided with a hand operated valve 38 disposed exteriorly of the collar 9, the valve casing having attached thereto the usual flexible dispensing hose 39.

The lower and open end of the discharge tube or chamber 37 is closed by a cap nut 40, and this cap nut has an angle passage in 80 which is screwed a drain cock 41. Also the cap nut has screwed thereon a packing box 42 through which passes the operating rod 43. The operating rod is connected by a pin to the lower end of the discharge tube 44, the 85 latter having its upper end received in the tank 16 and the said tube, of course, passes through the packing 36.

One of the rods which I have designated by the numeral 21 is hollow, and passing through 90 this hollow rod there is an air vent pipe 45 which communicates with the widened or enlarged bore of the coupling 35 and with the top of the tank 16.

The operating rod 43 has fixed thereon a 95 handle 46 that passes through a vertically disposed elongated opening in one side of the standard or casing 4. In this connection it should be stated that the operating handle for the pump 31 passes through an opening 100 in the opposite side of the member 4. One of the rods 5 is disposed opposite the first mentioned opening, which latter for distinction is indicated by the numeral 47. On this rod there is fixed upper and lower brackets 48 and 49, respectively. The lower bracket 49 has a 105 guide opening therethrough for the operating rod 43, the upper bracket 48 being shorter, and both of these brackets are connected together by a brace rod 50 as well as 110 by a second and inner rod 51. This last mentioned rod 51 is provided with equidistantly spaced lugs, nuts or other enlargements 52. Resting on each of the enlargements 52, and 115 swingable on the rod 51, there are the body portions 53 of stop members. These stop members are equal in number, are spaced away from each other the same distance as the indicators 28 and have inscribed thereon numerals corresponding to the numerals on 120 the indicators. The body 53 of each stop member has its upper portion contacted by a helical spring 54, each of the said springs exerting a tension between one of the stops 52 and the body of the said stop members 53. The body of the stop members 53 have on 125 one of their edges outwardly directed upper and lower fingers 55 and 56, respectively, the latter fingers serving as handles.

We will suppose that the tank is filled with 130

gasoline and that the entire contents are to be withdrawn therefrom. The operator exerts a downward pressure upon the rod 43 after he has swung the lowermost stop member 53 to bring its finger 56 in the path of contact with the hub of the operating handle 5. This brings the mouth of the dispensing tube against the packing nut on the base 12 of the tank, and consequently permits all of the 10 gasoline from the tank to flow by gravity through the tube 44, the discharge chamber 37, through the valve 38, and the dispensing pipe or hose 39. Should only one gallon of gasoline be required the uppermost stop 53 15 bearing the character 1 is swung to bring its finger 56 against the rod 43, and when the hub of the handle on the said rod 43 engages this stop the discharge tube 44 will be drawn downwardly through the tank 16 a sufficient 20 distance to permit exactly one gallon of gasoline being dispensed as above described. In a like manner the swinging of any of the stops into contact with the handle of the operating rod 43 will cause the desired quantity 25 of gasoline to be dispensed in a quick and accurate manner. Any air which may be created in the dispensing chamber will find an outlet through the vent pipe 45, and when the tank is not desired for use a suitable plate 30 covers the opening 47 and the handle for the pump 31 is removed. Any sediment in the discharge chamber will find an outlet through the cock 41.

I have herein set forth a simple and satisfactory embodiment of my invention as it now appears to me, but obviously the nature of the improvement is such as to necessarily render the same susceptible to changes and modifications. Therefore, it is to be understood 35 that I do not hold myself restricted to the precise details of construction herein set

forth and am entitled to make all such changes therefrom as fairly fall within the scope of what I claim, providing, of course, that such changes do not exceed the scope of 45 the invention or sacrifice any of the spirit thereof.

Having described the invention, I claim:—

1. In combination with a gasoline dispensing tank having a pipe adapted to be projected upwardly thereinto to various levels to determine the amount of liquid to be drained from said tank, means for limiting the downward movement of said pipe comprising a 50 rod attached thereto and having a handle thereon, a support adjacent said rod, collars on said support, stop members rotatably mounted on said support and resting on said collars, helical springs exerting tension between the under side of said collars and the 55 top of the next succeeding stop member, and fingers on said stop member adapted to contact with said handle to limit the downward movement of said pipe.

2. In combination with the tank of a gasoline dispensing apparatus, a tube adapted to be projected vertically into said tank, a rod extending downwardly from said tube, a support parallel to said rod and having stop members rotatably mounted thereon, said 60 stop members being limited in their downward movement on said support by collars fixed to the support, helical springs exerting tension between the lower side of said collars and the top of the next succeeding stop, said 65 stop members having a finger adapted to be brought adjacent the path of travel of said rod to indicate the correct positioning of the tube to permit the desired amount of liquid 70 to be drawn from the tank.

In testimony whereof I affix my signature.

JOLLY WILBUR THURSTON.
